United States Patent Office

Des. 206,550
Patented Dec. 27, 1966

206,550

INDICATING INSTRUMENT

Kenneth J. Cumming, Manchester, N.H., assignor to Honeywell Inc., Minneapolis, Minn., a corporation of Delaware

Filed Feb. 23, 1965, Ser. No. 83,945

Term of patent 14 years

(Cl. D52—6)

Fig. 3

Fig. 1

Fig. 2

FIGURE 1 is a perspective view of an indicating instrument showing my new design;

FIGURE 2 is a right side view thereof, the left side view being a mirror image; and

FIGURE 3 is a top view thereof, the bottom view being a mirror image.

The back side, not shown, of my design is conventional.

The essential features of the design are shown in full lines.

I claim:

The ornamental design for an indicating instrument, as shown and described.
